UNITED STATES PATENT OFFICE.

CLYDE W. PRICKETT, OF WINTerset, IOWA.

PROCESS FOR LAYING WOODEN FLOORS AND THE LIKE ON A CONCRETE BASE.

Application filed February 27, 1922. Serial No. 539,701.

To all whom it may concern:

Be it known that I, CLYDE W. PRICKETT, a citizen of the United States, and a resident of Winterset, in the county of Madison and 5 State of Iowa, have invented a certain new and useful Process for Laying Wooden Floors and the like on a Concrete Base, of which the following is a specification.

The object of my invention is to provide a 10 process for laying wooden floors and the like on a concrete base at a minimum of expense with a minimum number and difficulty of operations and with a minimum use of material.

15 A further object is to provide such a process, which will permit the free use of the concrete floor or base, after the base has been formed, and yet will enable the builder to readily and easily lay the wooden floor, 20 after the other structure has been completed.

More particularly it is my object to provide a process of the kind under consideration, wherein a concrete base is laid, having anchored to it such means for holding 25 stringers or sleepers, which means are so arranged and so constructed that while properly connected with the concrete base, they will be out of the way during the period after the base has been poured, until 30 the time arrives for building or placing the floor above the base.

Further objects will appear in connection with the further description and explanation of my process.

35 In order to more fully explain and illustrate my process, I have shown herewith certain drawings, illustrating means, whereby my process may be carried out, and the building structure during such steps and 40 stages of the process.

In the accompanying drawings,

Figure 1 shows a perspective view, partly in section of a concrete base as laid with certain floor clips installed therein, the view being also adapted to illustrate the method 45 of installing the floor clips.

Figure 2 shows a similar view with the engaging members of the floor clips, which are designed to be fastened to the stringers, 50 in their upright position.

Figure 3 shows a perspective view of the same space with the floor partly laid; and

55 Figure 4 shows a perspective view of one of the floor clips in condition to be placed in the concrete base.

Prior to the time when my floor clip

covered by my patent hereinbefore mentioned, went on the market, the ordinary way of laying a wooden floor on a concrete base, was as I will now describe.

A concrete base or slab was poured. Stringers having beveled edges were laid on the concrete at the proper elevation to receive the finished floor, after it had had an opportunity to harden, and were anchored 60 and shored from above, by braces connected with the ceiling. It was quite difficult to hold them in place.

It was the custom, after these stringers had been anchored by long wooden braces 70 and the like, to then pour another layer of concrete, in which the stringers would thus be embedded.

The above described method for laying the 75 stringers for supporting the wooden floor was complicated, slow, clumsy and very expensive.

Also it involved the laying of very heavy concrete bases.

The method, which I have herein described, so far as I know, is novel. Prior to the use of my clips, clips of a somewhat general nature, have been used for deadening sound. These clips to which I refer, usually had felt or other sound deadening 85 strips attached to them, but they were not used, as I use my clip in my process.

In my process, a layer of concrete base indicated in the accompanying drawings, by the reference numeral 10, is first poured. 90 Before this concrete base has hardened too much, I anchor in it, the rows of clips, to which the sleepers for supporting the floor are subsequently secured.

The clips may be of different kinds, but I 95 preferably use those, such as are illustrated in Figure 4. The clip, thus illustrated, comprises a central, horizontal member 11, having at its ends opposite, downwardly projecting portions 12. The material, if made 100 from a single strip, is arranged with upwardly projecting portions extending from the lower ends of the portions 12, and indicated by the numeral 13. The portions 13 are designed to be long enough to project 105 substantially above the horizontal member 11.

The upwardly projecting members 13 should have some means, such for instance, as the holes 14, to receive and hold nails, 110 driven into the stringers or sleepers.

The clips are so anchored in the concrete

base 10 that a row of them will be arranged to receive a sleeper or stringer 15 between the upwardly extending members 13 of the respective clips.

5. The clips may be made of one piece each. They may be formed of strips, as shown herein, or may be made of twisted wire or of single pieces of wire. They may be made in single pieces or in more than one part.

10. It is, however, important that they should be made of such material, that the upwardly projecting part of the portions 13 may be bent downwardly, to horizontal position, so as to be flat above the concrete base 10. It is 15 not so important that the portions of the members 13 above the horizontal member 11 be extended upwardly vertically or that they lie flat at the time of the placing of the clips in the concrete, but it is important that 20 afterwards during the use of the floor for other construction work, the upper portions of the clip, should lie flat on the concrete.

It is obvious that the portions of the member 13 can be bent over each other, as 25 shown in Figure 4, or could be bent away from each other, and the same advantageous results obtained.

It is important that after the concrete base is laid, the clips should be placed there- 30 in before the base is hardened, and the clips should then be laid flat during the use of the concrete base, while other parts of the building construction is carried on.

Ordinarily in building, the concrete base 35 is laid and thereafter a great deal of other construction is completed, and the wooden floor is one of the last parts of the work done.

It is obvious that the clips must be in- 40 serted when the concrete base is soft, and it is extremely desirable that the floor be capable of use, without having projecting devices that would trip the workmen or that would be likely to be injured during the use 45 of the concrete base as a floor.

The importance of a clip therefor, which can be laid flat, so that it will not do any harm to the workmen, and will not interfere with the ordinary use of the concrete 50 base as a floor, and yet can be straightened up for holding the stringers or sleepers, when the proper time comes, will be obvious.

Various methods may be used for placing the clips in the concrete base.

55. For illustration, I have shown two boards 16 held in spaced relation lying flat, by means of connecting strips 17. In the forward edge of each board is a saw kerf 18, so arranged and located as to properly indicate the place for anchoring the strips, when the boards are laid on the concrete base.

The strips 17 project far enough from the boards 16 so as to indicate the distance be- 60 tween successive rows of the clips.

After the concrete base has been laid, the clips installed and left flat out, and the intermediate construction has been completed, then the wooden floor is laid.

In preparing for laying the wooden floor, 70 the flat portions of the members 13 are raised, so that they stand upright, as shown for instance in Figure 3.

A stringer 15 is laid in each row of clips. 75 Nails may be driven through the holes 14 into the stringers 15. The stringers will thus be firmly held in position, and there is no need to embed them in concrete.

I therefore am able to save or avoid the 80 pouring of the second layer of concrete, which has commonly been employed heretofore.

This not only saves materials and labor 85 in the floor itself, but greatly reduces the weight of the concrete floor and reduces the strength necessary in the retaining and supporting wall.

After the stringers 15 have been placed in position, the flooring 19 may be laid in the 90 usual way.

It is, of course, understood that sometimes two layers of flooring are placed on the stringers 18.

If desired, the stringers may be embedded 95 in concrete, but this is usually neither desirable nor necessary.

In summary, I can scarcely over emphasize the importance of the feature of placing in the slab of concrete the clips having the portions above the concrete, which are 100 folded over to lie flat, to permit the free use of the slab as a floor during further construction work without interfering with shoveling, hauling and otherwise.

The laying of the wood finish floor is 105 usually one of the last operations and is easily done, when the clips are straightened up and the sleepers secured thereto.

Where my method is employed, I entirely 110 obviate the necessity of using the second layer of concrete, and effect a tremendous saving in time, expense, labor and weight of material. My floors do not creak and become loose, as is the case where the wooden blocks are used, under one of the 115 present systems mentioned above.

I claim as my invention:

1. The process of constructing a wooden floor on a concrete base comprising the forming of a soft plastic base, inserting in 120 alined rows therein from above by vertical movement spaced stiff legs provided with a connecting piece above the base bottom and horizontal members, then utilizing the base when hardened for further building operations which may be done without interference from the clips, then raising the horizontal members to upright position, securing sleepers therebetween and securing wood flooring to the sleepers. 130

2. A process comprising the forming of a plastic base, inserting therein from above with a vertical movement stiff legs of preformed clips having sleeper engaging portions lying flat above the base and provided with a connecting piece, then using the base as a floor during further building operations, then bending portions of the clip to upright position, securing sleepers thereto and securing a wooden floor to the sleepers. 55
3. A floor construction building process comprising the forming of a concrete floor slab base then inserting spaced stiff legs of clips provided with connected portions in the floor slab from above with a vertical downward movement while the slab is yet in a plastic condition, permitting the slab with the clips therein to harden, then using the floor slab during further building operations without interference from the clips therein, moving parts of the clips to position for receiving a sleeper thereagainst, then placing sleepers adjacent to said last parts, securing said parts to the sleeper for anchoring the sleeper to the floor slab, and securing a wooden floor to the sleepers. 60
4. A floor construction building process comprising the forming of a concrete floor slab base, then inserting spaced stiff legs of clips having connected portions in the floor slab from above with a vertical downward movement while the slab is yet in a plastic condition, permitting the slab with the clips therein to harden, then using the floor slab during further building operations without interference from the clips therein, then moving parts of the clips away from the floor slab so that they project thereabove in substantially vertical position, then placing sleepers between said parts with their sides resting against said parts, securing said parts to the sleeper whereby the clips are the sole means of anchoring the sleepers to the concrete slab and thereafter securing a wooden floor to the sleepers. 65
5. The process of constructing a wooden floor on a concrete base comprising the forming of a soft plastic base, inserting therein in aligned rows, from above with a vertical movement, legs of preformed clips having connecting means above the lower ends of the legs, arranging sleeper engaging portions of the clip flat above the base, using the base after it has hardened, as a floor for further building operations, raising the said portions to upright position and securing sleepers between them and securing wood flooring to the sleepers. 70
6. A process comprising the forming of a plastic base, inserting therein from above with a vertical movement stiff legs of preformed clips having sleeper engaging portions lying flat above the base and provided with a connecting piece above the lower ends of the legs, then using the base as a floor during further building operations, then bending portions of the clip to upright position, securing sleepers thereto and securing a wooden floor to the sleepers. 75
7. A process for constructing a wooden floor on a concrete base, comprising the forming of a plastic base, inserting therein while the base is soft, from above with a vertical movement stiff legs of preformed clips, each having a sleeper engaging portion adapted to lie flat above the base and provided with connecting means above the lower ends of the legs, then using the base as a floor during further building operations, then raising the sleeper engaging portion of the clips to upright position, securing sleepers thereto, and securing a wooden floor to the sleepers. 80
8. The process of constructing a wooden floor on a concrete base comprising the forming of a soft plastic base, inserting therein in aligned rows, legs of preformed clips having connecting means above the lower ends of the legs, arranging sleeper engaging portions of the clip flat above the base, using the base after it has hardened, as a floor for further building operations, raising the said portions to upright position and securing sleepers between them and securing wood flooring to the sleepers. 85
9. A process comprising the forming of a plastic base, inserting therein from above, stiff legs of preformed clips having sleeper engaging portions lying flat above the base and provided with a connecting piece, above the lower ends of the legs, then using as a floor during further building operations, then bending portions of the clip to upright position, securing sleepers thereto and securing a wooden floor to the sleepers. 90
10. The process of constructing a wooden floor on a concrete base comprising the forming of a soft plastic base, inserting therein in aligned rows, from above with a vertical movement, legs of preformed clips having connecting means above the lower ends of the legs, arranging sleeper engaging portions of the clip flat above the base, using the base after it has hardened, as a floor for further building operations, raising the said portions to upright position, securing sleepers between them and securing wood flooring to the sleepers. 95
11. The process of constructing a wooden floor on a concrete base comprising the forming of a soft plastic base, inserting therein in aligned rows, from above with a vertical movement, legs of preformed clips having connecting means above the lower ends of the legs, arranging sleeper engaging portions of the clip flat above the base, using the base after it has hardened, as a floor for further building operations, raising the said portions to upright position, securing sleepers between them and securing wood flooring to the sleepers. 100
12. The process of constructing a wooden floor on a concrete base comprising the forming of a soft plastic base, inserting therein in aligned rows, from above with a vertical movement, legs of preformed clips having connecting means above the lower ends of the legs, arranging sleeper engaging portions of the clip flat above the base, using the base after it has hardened, as a floor for further building operations, then bending portions of the clip to upright position, securing sleepers thereto and securing a wooden floor to the sleepers. 105

Des Moines, Iowa, February 21, 1922.
